(57) **CLAIM**

The ornamental design for a scope ring as shown and described.

DESCRIPTION

FIG. 1 is an upper perspective view of the scope ring embodying the new design;

FIG. 2 is a rear view thereof;

FIG. 3 is a front view thereof;

FIG. 4 is a right side view thereof;

FIG. 5 is a left side view thereof;

FIG. 6 is a top view thereof; and,

FIG. 7 is a bottom view thereof.

The broken line in the figures depict portions of the scope ring that form no part of the claimed design. The broken lines immediately adjacent to the shaded portions of the design form the boundaries of the claim that form no part thereof. The scope ring includes a symbolic break in FIGS. 1-5 drawn in broken lines. The broken lines and the area between break lines forms no part of the claimed design.
